RAILWAY TRAFFIC CONTROLLING
APPARATUS

Henry S. Young, Wilkinsburg, and Ronald A. McCann, Swissvale, Pa., assignors to The Union Switch & Signal Company, Swissvale, Pa., a corporation of Pennsylvania

Application September 29, 1938, Serial No. 232,378

10 Claims. (Cl. 246—130)

Our invention relates to railway traffic controlling apparatus, and has for an object the provision of novel and improved means for governing a control device whereby a momentary loss of train shunt within a control section does not affect the operation of the control device. Other objects and advantages of our invention will appear as the specification progresses.

We shall describe one form of apparatus embodying our invention, and shall then point out the novel features thereof in claims.

The accompanying drawing is a diagrammatic view showing a preferred form of apparatus embodying our invention when applied to the control of a highway crossing signal.

Referring to the drawing, the reference characters **1** and **1a** designate the traffic rails of a stretch of railway track **X** over which traffic moves in both directions. Rails **1** and **1a** are divided by means of the usual insulated rail joints **2** into relatively long sections **D—E** and **F—G** separated from each other by a relatively short section **E—F**, which is intersected by a highway **H**. Located adjacent the intersection is a highway crossing signal **S**, which may be of any suitable type, but which, as here shown, is an audible signal in the form of an electric bell. Sections **D—E** and **F—G** usually will be of such length suitable to provide an adequate warning period to highway users of the approach of a train to the intersection. Section **E—F** will usually be of such length as to completely include the intersection.

Sections **D—E**, **E—F**, and **F—G** are provided with track circuits comprising in each instance a suitable source of current, such as a track battery **3**, connected across the track rails at one end of the section, and a track relay, designated by the reference characters **TR1**, **TR2**, and **TR3**, respectively, connected across the track rails at the other end of the section.

The reference characters **SR1** and **SR2** designate stick relays associated with track relays **TR1** and **TR3**, respectively. Relay **SR1** is normally energized over a stick circuit passing from terminal **B** of a suitable source of current, such as a battery not shown, through front contact **6** of relay **TR1**, front contact **7** of relay **SR1**, and the winding of relay **SR1** to the other terminal **C** of the current source. The relay **SR2** is normally energized over a stick circuit passing from terminal **B** through front contact **17** of relay **TR3**, front contact **18** of relay **SR2**, and the winding of relay **SR2** to terminal **C**. The relays **SR1** and **SR2** are provided each with a first and a second

pick-up circuit and which circuits will be described more fully hereinafter.

The reference character **TER1** designates a time element relay which is governed jointly by relay **TR1** and relay **SR1**, and the reference character **TER2** designates a time element relay governed jointly by relay **TR3** and relay **SR2**. The time element relay **TER1** and **TER2** may be of any suitable type, such as, for example, the type disclosed in the United States Letters Patent No. 2,114,895, granted on April 19, 1938 to H. E. Ashworth for Thermal relays. These relays are each provided with a normally open contact which closes within a predetermined interval, of, say, 10 seconds, after the relay is energized.

Two auxiliary relays **AR1** and **AR2** are provided for checking the operation of the thermal relays **TER1** and **TER2**, respectively. The circuits for controlling the auxiliary relays **AR1** and **AR2** will be pointed out later.

Directional control of the highway crossing signal **S** is established through the medium of an interlocking relay **XR**. The interlocking relay **XR** may be of any suitable type, such as, for example, the relay covered by United States Letters Patent No. 1,799,629, granted to W. K. Lockhart and T. J. O'Meara on April 7, 1931. This type of relay is well-known and is characterized by the fact that when the left-hand winding **W1** is deenergized, the downward movement of the armature associated therewith operates a mechanical locking device which keeps the armature associated with the right-hand winding **W2** "locked up" in approximately its mid position, so that the subsequent deenergization of winding **W2** while winding **W1** is still deenergized cannot close back contact **24**. Similarly, if the right-hand winding **W2** is first to become deenergized, then back contact **25** is prevented from closing when the left-hand winding **W1** becomes deenergized during the interval that winding **W2** is still deenergized. Relay **XR** is also provided with front contacts **26** and **27** associated with windings **W1** and **W2**, respectively, which have what we shall term "flagman" adjustments. That is to say, each "flagman" contact remains closed when its associated armature is in its "locked up" position. Winding **W1** is provided with an energizing circuit which may be traced from terminal **B** through front contact **10** in multiple with front contact **11** of relay **TR2**, front contact **9** of relay **SR1**, back contact **12** of relay **AR1** in multiple with the front "flagman" contact **26** of winding **W1** of relay **XR**, and the winding **W1** of relay **XR** to terminal **C**. Winding **W2** is provided with an energizing cir-

cuit passing from terminal B through front contact 10 in multiple with front contact 11 of relay TR2, front contact 19 of relay SR2, back contact 32 of relay AR2 in multiple with front "flagman" contact 27 of winding W2 of relay XR, and the winding W2 of relay XR to terminal C. Hence, winding W1 of relay XR is governed jointly by track relay TR2, stick relay SR1 and auxiliary relay AR1, but at times front "flagman" contact 26 of winding W1 nullifies the control exerted by relay AR1 over winding W1. Winding W2 is governed jointly by relay TR2, relay SR2, and relay AR2, with front "flagman" contact 27 of winding W2 at times nullifying the control of relay AR2 over winding W2.

The immediate operating circuit for signal S passes from terminal B through back contact 25 of winding W1 or back contact 24 of winding W2 of relay XR, and the winding of signal S to terminal C.

The apparatus is in its normal condition, as shown in the drawing, when sections D—E, E—F, and F—G are unoccupied. In this condition of the apparatus, the track relays TR1, TR2, and TR3 are energized, the stick relays SR1 and SR2 are energized over their respective stick circuits, windings W1 and W2 are energized, and relays TER1, TER2, AR1, AR2, and signal S are deenergized.

Having thus described the various elements of the apparatus embodying our invention, we shall explain their operation for an eastbound train, and shall at the same time trace the circuits controlling each part of the apparatus.

When an eastbound train, that is, a train operating from left to right in the drawing, enters section D—E, relay TR1 is deenergized and releases to open front contact 6 and thereby open the stick circuit for relay SR1 with the result that relay SR1 becomes deenergized and releases to open front contact 1 and thereby open its stick circuit, and closes back contact 8 to prepare an energizing circuit for relay TER1. The release of relay SR1 also opens front contact 9 and thereby opens the control circuit for winding W1 so that winding W1 releases to close back contact 25 and thereby initiate the operation of signal S.

In the event a momentary loss of train shunt occurs while the train occupies section D—E, the track relay TR1 might pick up, following the fluctuation in the train shunt, but the operation of the control device, that is, signal S, is unaffected, since relay TR1 ordinarily will release again prior to the completion of the cycle of operation necessary to effect the energization of winding W1 and the consequent deenergization of signal S. This cycle of operation is initiated when front contact 6 of relay TR1 closes when the track relay picks up, and consists of the following steps:

The energization of relay TER1 until such time as contact 13 closes; the energization and deenergization of relay AR1; and the energization of relay SR1, which relay then completes the control circuit for winding W1. For a more complete understanding of our invention, we shall describe in detail this cycle of operation of the apparatus, it being understood that relay TR1 is assumed to remain energized for the entire interval required for the apparatus to complete its cycle of operation.

The energization of relay TER1 is effected over a circuit passing from terminal B through front contact 6 of relay TR1, back contact 8 of relay SR1, the operating element of relay TER1, and back contact 14 of relay AR1 to terminal C. The

energization of relay TER1 for its predetermined time interval will result in contact 13 closing the pick-up circuit for relay AR1, this circuit passing from terminal B through front contact 6 of relay TR1, back contact 8 of relay SR1, contact 13 of relay TER1, and the winding of relay AR1 to terminal C. Relay AR1 picks up upon becoming energized to close front contact 15 and thereby complete a stick circuit for that relay passing from terminal B through front contact 15 of relay AR1, contact 13 of relay TER1, and the winding of relay AR1 to terminal C, and to open back contacts 12 and 14, the opening of back contact 14 opening the energizing circuit for the operating element of relay TER1, and the opening of back contact 12 opening the previously traced control circuit for winding W1. The picking up of relay AR1 also completes the second pick-up circuit for relay SR1, which may be traced from terminal B through front contact 6 of relay TR1, front contact 16 of relay AR1, and the winding of relay SR1 to terminal C, whereupon relay SR1 picks up to close front contact 9 interposed in the control circuit for winding W1, but winding W1 remains deenergized until the control circuit for winding W1 is completed at back contact 12 of relay AR1. This control circuit is completed when the contact 13 of relay TER1 opens at the end of a short interval after the operating element of the relay TER1 is deenergized. The opening of contact 13 of relay TER1 opens the stick circuit for relay AR1, with the result that relay AR1 releases to close back contact 12 and thereby complete the control circuit for winding W1, and to open front contact 16 and thereby open the pick-up circuit for relay SR1, the relay SR1 being retained energized over its stick circuit. The complete cycle of operation aforementioned is now completed, so that in the event that relay TR1 is not released, winding W1 becomes energized to deenergize signal S. However, relay TR1 remaining picked up for the full interval required for the apparatus to complete its cycle of operation is a very remote possibility, since ordinarily a loss of shunt within a control section is only of very few seconds duration, and the train shunt is normally restored and relay TR1 released prior to the control circuit for winding W1 being completed, with the result that the control circuit for winding W1 remains open and the operation of signal S is not affected by the picking up and releasing of the track relay in response to variations in train shunt in the control section. It is understood, of course, that the period of time required for such cycle of operations may be selected by proper proportioning of the parts to best suit the different conditions existing at each location wherein such apparatus is installed.

When the train enters section E—F, relay TR2 releases to open front contacts 10 and 11 which are interposed in the control circuits for windings W1 and W2, with the result that winding W2 releases to its locked position.

When the train enters section F—G, relay TR3 releases to open front contact 17, thereby opening the stick circuit for relay SR2 with the result that relay SR2 is deenergized and releases to open front contacts 18 and 19, and to close back contact 20. The opening of front contact 18 of relay SR2 opens its stick circuit, the opening of front contact 19 opens the previously traced control circuit for winding W2, while the closing of back contact 20 prepares an energizing circuit for relay TER2.

When the train vacates section D—E, relay TR1 picks up to close front contact 21 and thereby complete a first pick-up circuit for relay SR1, which circuit may be traced from terminal B through back contact 22 of relay TR3, front contact 21 of relay TR1 and the winding of relay SR1 to terminal C. Relay SR1 becomes energized and picks up to close front contact 7, thereby completing its stick circuit including front contact 6 of relay TR1, and to close front contact 9, thereby preparing the control circuit for winding W1. It should be noted that when the train vacates the section D—E, relay SR1 is picked up over its first pick-up circuit to prepare the control circuit for winding W1 independently of the time element relay TER1, with the result that the delay period of the time element relay resulting from the complete cycle of operation necessary to close the second pick-up circuit for relay SR1 is not ordinarily employed.

When the train vacates section E—F, relay TR2 picks up to close front contacts 10 and 11 and thereby completes the control circuit for winding W1, whereupon winding W1 picks up to open back contact 25 with the result that the operation of signal S is terminated.

It should be noted that back contact 12 of relay AR1 must be closed in order to enable relay TR2 to complete the control circuit for winding W1. It can be seen that in the event the above described cycle of operations has been effected while the train occupied section D—E, back contact 12 of relay AR1 will be closed only if contact 13 of relay TER1 is opened, since contact 13 governs the stick circuit for relay AR1. It follows that back contact 12 of relay AR1 provides a check upon the normally open position of contact 13 of relay TER1, since if the relay TER1 fails to open contact 13, the signal S will continue to operate and so denote the improper condition existing within the apparatus.

When the train vacates section F—G, relay TR3 picks up to open back contact 22 and thereby open the finest pick-up circuit for relay SR1, and to close front contacts 17 and 23, the closing of front contact 17 completing an energizing circuit for relay TER2 passing from terminal B through front contact 17 of relay TR3, back contact 20 of relay SR2, the operating element of relay TER2 and back contact 23 of relay AR2 to terminal C. At the end of its predetermined time interval, relay TER2 closes contact 29, thereby completing a pick-up circuit for relay AR2 passing from terminal B through front contact 17 of relay TR3, back contact 29 of relay SR2, contact 29 of relay TER2, and the winding of relay AR2 to terminal C. Relay AR2 is energized and picks up to close front contact 30 and thereby complete a stick circuit for that relay through front contact 30 and contact 29 of relay TER2, and to close front contact 31, thereby completing the second pick-up circuit for relay SR2 passing from terminal B through front contact 17 of relay TR3, front contact 31 of relay AR2, and the winding of relay SR2 to terminal C. The picking up of relay AR2 also opens back contact 28 which opens the circuit for the operating element of relay TER2 and back contact 32, which is interposed in the control circuit for winding W2.

Relay SR2 now picks up to open back contact 20, thereby opening the pick-up circuit for relay AR2, and to close front contacts 18 and 19, the closing of front contact 18 completing the stick circuit for relay SR2, and the closing of front

contact 19 completing the control circuit for winding W2 passing from terminal B through front contact 10 and front contact 11, in multiple, of relay TR2, front contact 19 of relay SR2, front "flagman" contact 27 of winding W2, and the winding W2 of relay XR to terminal C, with the result that winding W2 picks up.

After relay TER2 has been deenergized for a brief interval, contact 29 opens to open the stick circuit for relay AR2, with the result that relay AR2 releases and the apparatus is restored to its normal condition.

In the event that a loss of shunt occurs in section F—G while the train is receding from the intersection, the directional control of signal S is maintained by virtue of the cycle of operation effected by relays TER2, AR2 and SR2, as described in connection with the train vacating the section F—G. It follows that since a loss of train shunt is ordinarily of quite short duration, the shunt will be restored and the track relay TR2 released prior to the apparatus completing its cycle, with the result that the winding W2 remains deenergized so that the directional control of signal S is not affected.

It should be noted front "flagman" contact 27 of winding W2 provides a shunt path around back contact 32 of relay AR2 in the control circuit for winding W2. It should further be noted that although back contact 32 of relay AR2 may be opened by virtue of the failure of relay TER2 to open contact 29 and thereby open the stick circuit for relay AR2, whereby relay AR2 is maintained energized, the winding W2 will pick up to restore the interlocking relay XR to its normal condition when section F—G is vacated by the eastbound train. In the event that relay TER2 fails to open contact 29, it can be seen that when a westbound train approaches the intersection, signal S will operate properly to warn the highway users of the approach of a train, and after the train has cleared the intersection, signal S will continue to operate to indicate the failure of relay TER2 to open contact 29 since the control circuit for winding W2 is open at back contact 32 of relay AR2 and at front "flagman" contact 27 of winding W2. It follows that back contact 32 of relay AR2 serves to check the normally open position of contact 29 for relay TER2 by causing the signal S to continue to operate when relay TER2 fails to open its contact.

The operation of the apparatus of a westbound train is similar to the operation just described for an eastbound train, and it is believed therefore that this latter operation will be apparent from the foregoing description together with an inspection of the drawing without further detailed explanation.

Although we have herein shown and described only one form of apparatus embodying our invention, it is understood that various changes and modifications may be made therein within the scope of the appended claims without departing from the spirit and scope of our invention.

Having thus described our invention, what we claim is:

1. In combination, a stretch of railway track provided with a track circuit including a track relay, a stick relay normally energized over a stick circuit including a front contact of said track relay, a time element relay, circuit means for energizing said time element relay including a front contact of said track relay and a back contact of said stick relay, an auxiliary relay, an energizing circuit for said auxiliary relay including

said circuit means together with a contact of said time element relay closed only in the energized condition of the time element relay, a pick-up circuit for said stick relay including a front contact of said track relay and a front contact of said auxiliary relay, and a control circuit including a front contact of said stick relay.

2. In combination, a stretch of railway track intersected by a highway and divided into a first 10 and a second track section extending in opposite directions from the intersection, a highway crossing signal located at such intersection, a track circuit for said first section including a first track relay, a track circuit for said second section including a second track relay, a first stick relay normally energized over a stick circuit governed by said first track relay, a second stick relay normally energized over a stick circuit governed by said second track relay, a first time element relay 15 governed jointly by said first track relay and said first stick relay, a second time element relay governed jointly by said second track relay and said second stick relay, a first auxiliary relay; a pick-up circuit for said first auxiliary relay governed jointly by said first stick relay and said first time element relay; a second auxiliary relay; a pick-up circuit for said second auxiliary relay governed 20 jointly by said second track relay and said second time element relay; a stick circuit for said second auxiliary relay governed by said second time element relay, a pick-up circuit for said first stick relay, a stick circuit for said first auxiliary relay governed by said first time element relay; a second auxiliary relay; a pick-up circuit for said second auxiliary relay governed 25 jointly by said second track relay and said second time element relay; a stick circuit for said second auxiliary relay governed jointly by said second track relay and said second time element relay, a pick-up circuit for said second stick relay, a first stick relay normally energized over a stick circuit controlled by a front contact of said second track relay, a first time element relay 30 governed jointly by said first track relay and said first stick relay, means governed by said first time element relay for establishing a first pick-up circuit for said first stick relay, a second pick-up circuit for said first stick relay governed jointly by said first track relay and said second track relay, a second time element relay governed jointly by said second track relay and said second stick relay, means governed by said second time element relay for establishing a first pick-up circuit 35 for said second stick relay, a second pick-up circuit for said second stick relay governed jointly by said second track relay and said first track relay, operating means for operating said signal when a train approaches the intersection, a first 40 control circuit for said operating means governed by said first stick relay, and a second control circuit for said operating means governed by said second stick relay.

3. In combination, a stretch of railway track intersected by a highway and divided into a first and a second track section extending in opposite directions from the intersection, a highway crossing signal located at such intersection, a track circuit for said first section including a first track relay, a track circuit for said second section including a second track relay, a first stick relay normally energized over a stick circuit governed by said first track relay, a second stick relay normally energized over a stick circuit governed by said second track relay, a first time element relay governed jointly by said first track relay and said first stick relay, a second time element relay governed jointly by said second track relay and said second stick relay, a first auxiliary relay; a pick-up circuit for said first auxiliary relay governed jointly by said first track relay, said first stick relay and said first time element relay; a stick circuit for said first auxiliary relay governed by said first time element relay, a second auxiliary relay; a pick-up circuit for said second auxiliary relay governed jointly by said second track relay, said second stick relay and said second time element relay; a stick circuit for said second auxiliary relay governed by said second time element relay, a pick-up circuit for said first stick relay governed jointly by said first track relay and said first auxiliary relay, a pick- 45

up circuit for said second stick relay governed jointly by said second track relay and said second auxiliary relay, an interlocking relay having a first winding and a second winding, an operating circuit for said signal including a back contact of each of said windings of the interlocking relay, a first control circuit for said first winding governed jointly by said first stick relay and said first auxiliary relay, a second control circuit for said first winding governed jointly by said first stick relay and a flagman contact of said first stick relay, a first winding of the interlocking relay, a first control circuit for said second winding governed jointly by said second stick relay and said second auxiliary relay, and a second control circuit for said second winding governed jointly by said second stick relay and a flagman contact of said second stick relay.

4. In combination, a stretch of railway track intersected by a highway and divided into a first 20 and a second track section extending in opposite directions from the intersection, a track circuit for said first track section including a first track relay, a track circuit for said second track section including a second track relay, a first stick 25 relay normally energized over a stick circuit controlled by a front contact of said first track relay, a second stick relay normally energized over a stick circuit controlled by a front contact of said second track relay, a first time element relay 30 governed jointly by said first track relay and said first stick relay, means governed by said first time element relay for establishing a first pick-up circuit for said first stick relay, a second pick-up circuit for said first stick relay governed jointly by said first track relay and said second track relay, a second time element relay governed jointly by said second track relay and said second stick relay, means governed by said second time element relay for establishing a first pick-up circuit 35 for said second stick relay, a second pick-up circuit for said second stick relay governed jointly by said second track relay and said first track relay, operating means for operating said signal when a train approaches the intersection, a first 40 control circuit for said operating means governed by said first stick relay, and a second control circuit for said operating means governed by said second stick relay.

5. In combination, a stretch of railway track 50 divided into a first section and a second section separated from each other by a third section intersected by a highway, a highway crossing signal located at such intersection, a track circuit for said first section including a first track relay, a second track relay, a track circuit for said third section including a third track relay, a first stick relay normally energized over a stick circuit governed by said first track relay, a second stick relay normally energized over a stick circuit governed by said second track relay, a first time element relay governed jointly by said first track relay and said first stick relay, a second time element relay governed jointly by said second track relay and said second stick relay, a first auxiliary relay; a pick-up circuit for said first auxiliary relay governed jointly by said first track relay, said first stick relay, said first time element relay, a second auxiliary relay; a pick-up circuit for said second auxiliary relay governed jointly by said second track relay, said second stick relay, said second time element relay; a stick circuit for said first auxiliary relay governed by said first time element relay, a second auxiliary relay; a pick-up circuit for said second auxiliary relay governed jointly by said second track relay, said second stick relay and said second time element 55

relay; a stick circuit for said second auxiliary relay governed by said second time element relay, a pick-up circuit for said first stick relay governed jointly by said first track relay and said 5 first auxiliary relay, a pick-up circuit for said second stick relay governed jointly by said second track relay and said second auxiliary relay, an interlocking relay having a first and a second winding, an operating circuit for said signal including a back contact of each of said windings of the interlocking relay; a control circuit for said first winding governed jointly by said third track relay, said first stick relay and said first auxiliary relay; and a control circuit for said 10 second winding governed jointly by said third track relay, said second stick relay and said second auxiliary relay.

6. In combination, a stretch of railway track divided into a first section and a second section 20 separated from each other by a third section intersected by a highway, a highway crossing signal located at such intersection, a track circuit for said first section including a first track relay, a track circuit for said second section including a second track relay, a track circuit for said third section including a third track relay, a first stick relay normally energized over a stick circuit governed by said first track relay, a second stick relay normally energized over a stick circuit governed by said second track relay, a first time element relay governed jointly by said first track relay and said first stick relay, a second time element relay governed jointly by said second track relay and said second stick relay, a first auxiliary 25 relay; a pick-up circuit for said first auxiliary relay governed jointly by said first track relay, said first stick relay and said first time element relay; a stick circuit for said first auxiliary relay governed by said first time element relay, a second auxiliary relay; a pick-up circuit for said second auxiliary relay governed jointly by said second track relay, said second stick relay and said second time element relay; a stick circuit for said second auxiliary relay governed by said second track relay and said second auxiliary relay, an interlocking relay having a first 30 and a second winding, an operating circuit for said signal including a back contact of each of said windings of the interlocking relay; a first control circuit for said first winding governed by said third track relay, said first stick relay and said first auxiliary relay; a second control circuit for said first winding governed by said third track relay, said first stick relay and a flagman contact of said first winding; a first control circuit for 35 said second winding governed by said third track relay, said second stick relay and said second auxiliary relay; and a second control circuit for said second winding governed by said third track relay, said second stick relay and a flagman contact of said second winding.

7. The combination with a section of railway track having a track relay responsive to traffic conditions in the section and a stick relay normally energized over a stick circuit including a 40 front contact of the track relay, and a time element relay controlled over an energizing circuit which includes a front contact of the track relay and a back contact of the stick relay, said time element relay having a time contact which is operated from its normal position to an operated

position in a predetermined time interval of energization of the time element relay, of an auxiliary relay, an energizing circuit for said auxiliary relay including a front contact of the track relay and a back contact of the stick relay and the time contact of the time element relay in its operated position, and a pick-up circuit for the stick relay including a front contact of said auxiliary relay.

8. The combination with a section of railway track having a track relay responsive to traffic conditions in the section and a stick relay normally energized over a stick circuit including a front contact of the track relay, and a time element relay controlled over an energizing circuit which includes a front contact of the track relay, said time element relay having a time contact which is operated from its normal position to an operated position in a predetermined time interval of energization of the time element relay, of an auxiliary relay, a pick-up circuit for said auxiliary relay including a front contact of the track relay and a back contact of the stick relay and the time contact of the time element relay in its operated position, a stick circuit for said auxiliary relay including the time contact of the time element relay in its operated position, a pick-up circuit for the stick relay including a front contact of the track relay and a front contact of said auxiliary relay, and a control circuit including a front contact of the stick relay and also including a back contact of said auxiliary relay whereby the return of the time contact of the time element relay to its normal position is checked.

9. The combination with a section of railway track having a track relay responsive to traffic conditions in the section and a stick relay normally energized over a stick circuit including a front contact of the track relay, and a time element relay controlled over an energizing circuit which includes a front contact of the track relay and a back contact of the stick relay, said time element relay having a time contact which is operated from its normal position to an operated position in a predetermined time interval of energization of the time element relay, of circuit means controlled by a front contact of the track relay and the time contact of the time element relay in its operated position for establishing a pick-up circuit for the stick relay, a control circuit controlled by the stick relay, and means controlled by said circuit means interposed in said control circuit to check the return of the time contact of the time element relay to its normal position.

10. In combination, a stretch of railway track divided into two outer sections and an intermediate section, said intermediate section being intersected by a highway and provided with a highway crossing signal located at such intersection, a track circuit including a track relay for each of said sections, two stick relays one for each of the track relays of said two outer sections and each stick relay normally energized over a stick circuit controlled by a front contact of its associated track relay, a first pick-up circuit for each of said stick relays controlled by the other of the track relays of said two outer sections, means controlled by each track relay of said two outer sections for establishing a second pick-up circuit for its associated stick relay in a predetermined time interval after such track relay picks up, whereby a momentary loss of train

shunt in either outer section will not cause the associated stick relay to become energized, operating means for operating said signal, and means controlled by each of said stick relays and by the track relay of said intermediate section for controlling said operating means to initiate operation of said signal only for railway traffic moving

toward the intersection in said two outer sections but to operate said signal for railway traffic moving in either direction in said intermediate section and terminate operation of said signal after railway traffic clears said intermediate section. 5
